UNITED STATES PATENT OFFICE.

JOHN J. TOOMEY, OF CHICAGO, ILLINOIS, ASSIGNOR TO RATHBONE, SARD & CO., OF ALBANY, NEW YORK, A CORPORATION OF NEW YORK.

DESIGN FOR A COMBINATION COAL AND GAS RANGE.

54,479.

Specification for Design.

Patented Feb. 10, 1920.

Application filed April 26, 1918. Serial No. 231,042. Term of patent 14 years.

To all whom it may concern:

Be it known that I, JOHN J. TOOMEY, a citizen of the United States, and residing at Chicago, in the county of Cook and State of Illinois, have invented a new, original and ornamental Design for a Combination Coal and Gas Range, of which the following is a specification, reference being had to the accompanying drawing, forming part thereof.

The figure is a front view of a combination coal and gas range showing my new design. The gas range is capable of being

moved vertically into a position parallel with the back of the range and then forms the design which is covered by companion application of even date herewith.

I claim—

The ornamental design for a combination coal and gas range as shown.

Dated, Chicago, April 8, 1918.

JOHN J. TOOMEY.
